UNITED STATES PATENT OFFICE.

LUNA MAY ENNIS, OF CHICAGO, ILLINOIS.

SANITARY SEAT-COVER FOR TOILETS.

1,284,077.

Specification of Letters Patent. Patented Nov. 5, 1918.

Application filed September 15, 1917. Serial No. 191,530.

To all whom it may concern:

Be it known that I, LUNA MAY ENNIS, a citizen of the United States, residing at Chicago, in the county of Cook and State 5 of Illinois, have invented a certain new and useful Improvement in Sanitary Seat-Covers for Toilets, of which the following is a specification.

My invention relates to improvements in 10 sanitary seat covers for toilets and the like, and has for one object to provide a new and improved form of such cover which will be adapted to fit and yieldingly cling to and hold itself in place on any ordinary toilet 15 seat. Another object is to provide such a cover made of paper or other suitable material which may be easily put in place and easily removed and thrown away. Another object is to provide a cover which will fold 20 into a preferably small compass so that it may be dispensed from any ordinary type of dispensing machine.

Other objects of my invention will of course appear from time to time in the specification.

My invention is illustrated more or less diagrammatically in the accompanying drawing, wherein—

Figure 1 is a plan view;

Fig. 2 is a section along the line 2—2 of Fig. 1;

Fig. 3 is a section similar to Fig. 2 with the central portion of the cover pushed down into the position of use;

Fig. 4 is a section through an alternate form;

Fig. 5 shows the cover folded along line 5—5 of Fig. 1;

Fig. 6 shows it folded along line 6—6 of Fig. 5;

Fig. 7 shows the cover folded as in Fig. 6 inclosed in a container;

Fig. 8 is a section on the line 8—8 of Fig. 7;

Fig. 9 shows a modified form of cover folded along its longer axis;

Fig. 10 shows the cover folded along line 10—10 of Fig. 9;

Fig. 11 is a section of the folded seat along the line 11—11 of Fig. 9;

Fig. 12 is a section through a container with a number of covers in place.

Fig. 13 is a section along the line 13—13 of Fig. 12.

Like parts are indicated by like letters throughout the specification.

A is a toilet seat apertured at A¹ and hinged to a support A².

B is a flexible removable sanitary seat cover shaped to conform to and adapted to 60 lie upon the seat. It has a forward downwardly curved portion B² adapted to conform closely to the curvature of the surface of the seat and so arranged that it extends beneath the seat as at B³. The seat cover is 65 apertured as at B⁴. The aperture, however, is smaller in cross sectional area than the aperture in the seat. The seat cover is made of paper, rubber, fabric or other suitable material and that part of the cover immediately adjacent or surrounding the aperture is slotted or cut as indicated at B⁵, so that when the cover is in use the material separates at the cuts and is depressed to conform to the curvature of the seat and extends down 70 into the aperture therein as shown in Fig. 3. The purpose of these cuts is merely to localize the separation of the material of which the cover is made and if a sufficiently elastic material is used these slits 75 80 will not be necessary. It is necessary, however, to provide means either by shaping the cover by providing sufficiently flexible cover or by cutting it whereby when the cover is in use the central portion around the central 85 aperture is bent down into and rests against and covers and protects the side walls of the perforation or aperture in the seat.

The rear portion of the cover is flat and so it may be easily folded on the line 5—5 90 as indicated without interfering with the shape of the front portion.

C is a cut in the front portion of the seat cover. This cut extends only through the curved portion B² and is so arranged that 95 when the cover first folded as in 5 is folded as in 6 the two curved portions B² B² on either side of the center line 6—6 slide one within another and engage one another so that the total thickness of the package is 100 but little greater than the total thickness of the cover itself in the unfolded position. C¹ is a box or carton adapted to contain the folded seat cover package and if desired it has a removable filler C² of wood, card- 105 board or other material put in to hold the top and bottom walls of the carton apart to prevent crushing of the shaped seat cover.

In a modified form D is a flange surrounding a portion of the front of the cover D¹ which cover is in every respect exactly the same as the cover B. This flange is straight but inclined and engages the front edge of the seat. This flange, however, may be folded flat so that as shown in Figs. 9, 10, and 11 the whole seat cover may be collapsed in a flat paper package. No carton is in this connection needed to protect and hold the parts together.

Figs. 12 and 13 show a dispensing apparatus wherein the seat covers are suspended over a filler block E in a box E¹ adapted to be fed one after another by a feed roller E² applied by a hand wheel E³. This roller engages the outer cover of the package and is adapted to force it out through the slot E⁴ in the bottom of the box E¹. The filler block E holds different parts of the covers apart and being pivoted at E⁵ to the case is yieldingly pressed to compress the covers toward the roller E² by means of the spring E⁶. It will be evident that while I have shown in my drawings an operative device, still many changes might be made both in size, shape and arrangement of parts without departing materially from the spirit of my invention and I wish, therefore, that my drawings be regarded as in a sense diagrammatic.

I claim:—

1. The combination with a toilet seat of a removable single piece seat cover shaped to conform to the toilet seat and adapted to lie upon and grip it, said seat cover being cut centrally so that the curved portions may fold one within another to form a package of relatively small compass.

2. The combination with a toilet seat of a removable single piece cover shaped to conform with the toilet seat and adapted to lie upon and grip it by its own shape and elasticity said seat cover having a centrally located hole in register with the hole in the seat and a downwardly depending flange located about its exterior and integral therewith, said seat cover being adapted to fold into a package of relatively small compass.

3. The combination with a toilet seat of a removable single piece cover shaped to conform with the toilet seat and adapted to lie upon and grip it by its own shape and elasticity said seat cover having a centrally located hole in register with the hole in the seat and a downwardly depending flange

located about its exterior and integral therewith said seat being adapted to fold into a package of relatively small compass.

4. The combination with a toilet seat of a removable single piece cover shaped to conform with the toilet seat and adapted to lie upon and grip it by its own shape and elasticity said seat cover having a centrally located hole in register with the hole in the seat and a downwardly depending flange located about its exterior and integral therewith said seat cover being cut centrally so that the curved portions may fold one within another to form a package of relatively small compass.

5. The combination with a toilet seat of a unit removable seat cover shaped to conform to the toilet seat and adapted to lie upon and grip it by means of its shape and elasticity said seat cover having a centrally located hole in the seat proper and two flanges, one about the outside of the cover and one about the hole, one of said flanges being adapted to positively grip and exert tension against the seat.

6. The combination with a toilet seat of a unit removable seat cover shaped to conform to the toilet seat and adapted to lie upon and grip it by means of its shape and elasticity said seat cover having a centrally located hole in register with the hole in the seat proper a flange depending about the outside of the cover adapted positively to grip the outside of the seat and exert tension thereon, and a flange depending about the edge of the hole.

7. The combination with a toilet seat of a unit removable seat cover shaped to conform to the toilet seat and adapted to lie upon and grip it by means of its shape and elasticity said seat cover having a centrally located hole in register with the hole in the seat proper a flange depending about the outside of the cover adapted positively to grip the outside of the seat and exert tension thereon, and a flange depending about the edge of the hole the latter flange exerting no tension.

In testimony whereof, I affix my signature in the presence of two witnesses this 6th day of September, 1917.

LUNA MAY ENNIS.
